SORTING MACHINE

David C. Cox, Lowell, Mich., assignor to Electric
Sorting Machine Company, Grand Rapids,
Mich.

Application August 3, 1938, Serial No. 222,787

29 Claims. (Cl. 209—111)

This invention relates to improvements in sorting machines.

The main objects of my invention are:

First, to provide a novel and improved machine for sorting articles on the basis of the relative color reflectivity thereof which is operative throughout a practically unlimited color range.

Second, to provide a sorting machine capable of classifying objects in accordance with hue as distinguished from brightness.

Third, to provide a sorting machine capable of classifying objects in accordance with both hue and brightness simultaneously.

Fourth, to provide a sorting machine which, with a single inspection, can make a plurality of totally independent decisions and subsequently make appropriate disposition of the inspected articles.

Fifth, to provide a sorting machine whose decisions may be based on two independent variables.

Sixth, to provide a machine of the type described having photoelectric means for scanning a plurality of articles to be sorted in combination with cathode ray tube means for receiving a primary signal originating in said photoelectric means, the said cathode ray means acting to originate a secondary signal in further photoelectric means viewing the cathode ray screen as exposed by a mask.

Seventh, to provide a machine of the type described embodying a cathode ray tube, the said tube constituting control means for determining the actuation of ejecting means.

Eighth, to provide a machine embodying a cathode ray tube adapted to have signals from a suitable originating source impressed on the deflecting plates thereof, and sentinel means associated with said cathode ray means and adapted to receive an indication therefrom.

Ninth, to provide a selective transmitting means including a cathode ray tube of the deflecting plate type and having a selectively masked fluorescent screen whereby only a predetermined portion of the screen is effective for light transmission.

Tenth, to provide in combination with a cathode ray tube means whereby light impingements on only a portion of its fluorescent screen are translated to subsequently operated means.

Eleventh, to provide a cathode ray controlling and actuating mechanism of broad utility.

Twelfth, to provide a novel sorting machine whose versatility is augmented by including means for making reflectivity measurements of two colors and means whereby acceptance or re-

jection may be determined in accordance with any prescribed values, either independent of or mutually dependent on said measurements.

Further objects relating to details and economies of my invention will definitely appear from the description to follow. The invention is defined in the claims.

A structure embodying the features of my invention is illustrated in the accompanying drawings, wherein:

Fig. 1 is a perspective view of a practical embodiment of my invention especially adapted or designed as a sorting machine for citrus fruit.

Fig. 2 is an enlarged fragmentary view in perspective, illustrating the rotatable article carrier, the ejector mechanism, and the article illuminating and scanning housing of my machine in operative relation to one another.

Fig. 3 is an enlarged fragmentary view of the illuminating and scanning housing and the article carrier, partially broken away and in vertical section to illustrate the construction and operative relation thereof.

Fig. 4 is a diagrammatic view illustrating the manner in which the photoelectric scanner views an article to analyze the color components thereof by light reflected therefrom.

Fig. 5 is a fragmentary perspective view illustrating the operative relation of a cathode ray tube, a mask, and a photoelectric sentinel tube which constitute important features of this invention.

Figs. 6 and 6A illustrate the wiring diagram for the electrical actuating circuit of the machine, the said diagram being broken into two parts along line A—A.

Fig. 7 is a representation of the screen of a cathode ray tube, having superposed thereon a diagram or chart illustrating the behavior of the cathode ray trace while the machine scans various articles.

Fig. 8 is a view illustrating a detail of construction or assembly of a modified embodiment of my invention.

The embodiment of my invention illustrated is a machine for sorting articles such as citrus fruits into various classifications according to color and, therefore, generally, degree of ripeness or condition. My invention is not, however, restricted in use to this field and is adaptable and may be employed for the sorting or color classification of any other articles, for example, coffee beans, peanuts, and the like, which, when subjected to light focused thereon from a source, are capable of reflecting rays of light having a

plurality of constituent colors. Furthermore, the machine possesses utility broadly as a sorting device irrespective of the basis on which the sorting is made and may avail itself of any characteristics of the articles, i. e., weight, hardness, strength, etc., which are capable of being proportionately expressed in the form of electric impulses.

In the embodiment illustrated, the advantages of my machine are emphasized in view of the fact that citrus fruits ordinarily vary through a wide range in the color thereof. It is of great practical importance to sort such fruits thoroughly in order to have articles of the same color crated together, or to remove overripe and underripe specimens or for other reasons, and it has heretofore been possible to accomplish such color sorting only by hand, a process which is slow and, in addition, by no means free from error. After a short interval of time, the most skilled sorter is unable to detect differences in color within a very appreciable range, due to fatigue of the eye; thereafter his work is totally unsatisfactory.

The present machine is eminently suited for the sorting of such articles or any articles having a considerable range of color variation, in view of the fact that its operation is based on an analysis of colored light reflected from the articles to be sorted and a consequent electro-mechanical sorting procedure in strict consonance with and by means of the information gained from this analysis of the articles. I am aware that it has hitherto been proposed to assort articles by differences in absolute intensity and differences in intensity of light reflected from the articles relative to a standard. In my prior copending applications Serial No. 711,374, filed February 15, 1934, now Patent No. 2,131,095 dated September 27, 1938, and Serial No. 49,727, filed November 14, 1935 now Patent No. 2,131,096, dated Sept. 27, 1938, I disclose machines assorting according to light intensity.

The present invention differs materially from prior art devices and the subject matter of the above noted applications in that in the instant invention I provide photoelectric means for viewing or scanning the articles through a plurality of color filters or screens so as to analyze light reflected from the articles according to the relative intensity of at least two of its color components.

In the specification to follow I employ the term "color reflectivity" to designate the property possessed by the surface of an article of reflecting a certain component of a multichromatic light to which it is exposed. However, I would not consider it a departure from the spirit of this invention should it be found desirable to use fluorescent light excited by a shorter wavelength. Although this would not involve true "reflectivity," nevertheless the effect on the light sensitive scanning instrumentality would be the same and I consider such an expedient within the scope of my invention.

In the machine of my invention, photoelectric impulses generated from such a scanning, that is, the separate primary signals, each proportional in strength to the percentage reflectivity of a certain color present in the light reflected from the surface of an article being sorted, are transmitted to the deflection plates of a cathode ray tube. The resulting electrostatic field set up between the respective deflection plates causes the electron stream or beam of the cathode ray

tube to be deflected in one direction or another on the fluorescent screen thereof. By associating a sentinel means unit in this embodiment and a photoelectric viewing means with the screen of the cathode ray tube and blocking out or masking desired portions of said screen, it is possible to expose the sentinel means to the spot or trace on the screen produced by the electron beam in whichever portion of the cathode ray screen it is desired. Bearing in mind that the beam deflection arises as a manifestation of the particular color of an article viewed, for instance, a defective article, it will be seen that the luminous spot or trace thus produced on the screen, if masked from the view of the viewing means, will cause no further action, but if it is permitted to be viewed by the photo-cell or -tube, the latter instantaneously originates a secondary impulse. The impulse generated in the said sentinel means may be then amplified and transmitted by suitable instrumentalities to an ejector mechanism and the undesirable article ejected.

The flexibility of my improved machine will be appreciated when it is realized that by suitably masking the cathode ray screen in an almost infinite number of ways an almost infinite number of gradations in relative color reflectivity of articles will be recognized by the photoelectric tube and any one thereof ejected if desired. On the other hand, if desired, the cathode ray screen may be so masked that all, except a certain class or coloration of articles, no matter how large or how small the class, will be ejected. It is only necessary that a certain grade or color of article be run through the machine in order to fix the point at which the cathode ray beam impinges on the screen when a given article passes the scanning tube; and the screen may be masked to pass only the beam trace characterizing articles of that color or of a range of color adjacent that color and accordingly set the machine to eject those articles, or, on the other hand, the mask may be selected to obstruct that beam trace and set the machine to eject all articles except those of that color or that range of color.

So far as I am aware, it is broadly novel to adapt the cathode ray tube to an assorting machine of the type described. Up to the present, the cathode ray tube has been restricted in its application to its use as an analysis or testing device, generally in the laboratory and more particularly in servicing radio receiving and transmitting apparatus, and in television. Its use in the cathode ray oscilloscope is well known. To my knowledge, all other practical or industrial adaptations of the cathode ray tube are at most experimental; the idea of employing the same as an element of a control apparatus in combination with a photoelectric viewing means and a selectively variable mask, either broadly or for the particular adaptation in a sorting machine, which I have deemed it expedient to illustrate, have, so far as I am aware, never occurred to anyone prior to myself.

Referring to the drawings, the reference numeral 1 indicates a supporting standard, table, or framework of the machine of my invention, the said framework rotatably supporting an article carrier wheel or conveyor 2 journaled on an upright axis and having a plurality of article carrying seats 3 thereon. A supporting bracket 4 on framework 1 carries a lamp housing 5 and an ejector mechanism generally indicated at 6,

consisting of a battery of ejector hammers 7 located at one side of and above wheel 2.

The framework 1 also supports the electrical amplifying and control apparatus generally indicated 8. This consists of a scanner amplifying section 9, a sentinel impulse amplifying and control section 10, and an intermediate enclosed section 11, wherein are mounted various control mechanisms to be hereinafter described. For a more particular description of the elements constituting these sections, reference will be had to the wiring diagram to be hereinafter described.

Adjacent the front of framework 1, I mount a housing 12 enclosing a plurality of cathode ray tubes 13. Cathode ray tubes of the RCA 908 type have been found to be satisfactory. This type of tube uses an electrostatic field between the plates to control deflection of the beam. It is obvious that electromagnetic deflection of the cathode ray beam is very similar to electrostatic deflection and it is of course possible to employ electromagnetically controlled tubes, such as the RCA 903, in my apparatus. However, voltage amplification is quite as easily accomplished as current amplification and it is believed to be definitely easier to approach absolute proportionality with voltage amplification.

Each tube is operatively associated with a photoelectric cell designated by the reference numeral 14 and for convenience hereinafter referred to as a "sentinel" tube, the said sentinel tubes being placed in operative relation directly adjacent the cathode ray screen (see Fig. 5). On this screen I place a mask 15 the function of which has been alluded to and will be more particularly pointed out. As illustrated in Fig. 1, each photoelectric sentinel tube 14 has a dome 16 enclosing the same and shielding it and also the cathode ray screen from external light. On one side of the machine, I mount a box 161 adapted to contain transformers, rectifiers, and filters, which will be hereinafter more particularly described.

Rearwardly of the cathode ray tube housing 12 and control section 10, I mount a delay commutator or detainer and a rotary switch generally designated 17 and 18, respectively. Means in the form of a motor (not shown) is provided for rotating article carrier wheel 2, and rotary switch 18 is driven from the wheel through a chain 19 so that it is rotated in timed relation with the article carrying wheel. In the present case, the relation is such that rotary switch 18 makes one rotation in the time it takes a pair of article seats 3 to pass a predetermined point. Detainer 17 is driven from rotary switch 18 by means of a chain 20 enclosed in a shield 21, the ratio of rotary switch angular speed to detainer angular speed being six to one. In other words, detainer 17 makes one rotation in the time it takes six article seats to pass a predetermined point. The detainer and rotary switch are provided with brush supporting brackets 22, 23, respectively, adjacent the same. The brushes carried by these brackets and the arrangement thereof with reference to the detainer and rotary switch, as well as the electrical connections from the brushes to the various other parts of the machine, will be hereinafter particularly referred to.

Referring to Figs. 2 and 3, the lamp housing 5 consists of a shell 24 which is substantially in the form of an ellipsoid internally, the internal exposed surface thereof being made up of a plu-

rality of mirrors 25 suitably secured as by cementing to the shell. An illuminating lamp 26 is arranged in the housing substantially at one focus thereof. The feed wire for the lamp is indicated by the reference numeral 27. Passages 28 are cut in the housing to provide for the passage of the article seats 3 of the conveyor and articles 29 thereon. The housing is positioned relative to the conveyor so that the articles 29 pass substantially through the other focus of the ellipsoid. A pair of reference background members 30 are secured to the housing at either side of the path of travel of the articles therethrough. These furnish a background for the article being viewed, and are viewed by the photoelectric scanner means during the normalizing operation to be hereinafter described.

I mount photoelectric article viewing means, generally designated 31, 32, in the lamp housing on either side of the path of travel of the articles, each consisting of a cylinder 33 inserted and fixedly secured in an opening in the housing and serving to mount a lens 34, a color filter 341, and a photoelectric article viewing tube. There are four such photoelectric tubes, designated by the reference numerals 35, 36, 37, and 38. For convenience, they will be hereinafter referred to as "scanner" tubes. The tubes are enclosed in housing 40 as illustrated in Figs. 2 and 3 and are arranged in the manner shown diagrammatically in Fig. 4. It will be noted that each scanner tube is provided with its separate lens and color filter. Likewise, each tube has a separate viewing cylinder 33 and the latter is provided with a projecting lid 41 adapted to shield its cell from the direct rays of lamp 26.

In the embodiment of my invention illustrated, the right side of the lemon is viewed by scanner tubes 36 and 38, the left side by scanner tubes 35 and 37. By using red-sensitive tubes, red-transmitting filters, and suitable associated amplifying apparatus, tubes 35 and 38 make an extremely rapid measurement of the reflectivity of the lemon with reference to red light. Similarly, 45 green-sensitive tubes 36 and 37, aided by green-isolating filters and an independent amplifying channel, make measurement of reflectivity with reference to green light. These measurements appear as voltages at the output of the amplifier, which will be detailed subsequently.

In Fig. 7 is presented graphically, using rectangular coordinates, red and green reflectivity measurements of several familiar kinds of fruit selected on account of color. An examination of this chart shows that very dark objects appear near the top, very bright ones near the bottom, gray ones somewhere on the line "black" to "white." Yellow objects locate near e, orange ones near f, dark red ones near g, pale green ones near c, deep green ones near a. Every object has a location somewhere on this color field and the location is in general characteristic of its appearance. Objects of the same hue appear on radial lines such as *mn* and *mp* originating at the apex marked "black." Their distance from this apex is a measure of their brightness. Arcs such as *tu* and *rs* indicate essentially zones of equal brightness.

It is evident from the diagram that the color of the tangerine *i* differs from that of the green apple *c* in hue while of practically the same brightness. The green apple *c*, on the other hand, differs from the lemon *b* in brightness, but registers almost identical hue. The light green lemon *b* may be distinguished from the dark

green lemon *a* by either hue or brightness, but the brightness distinction is much larger.

The various aforementioned objects whose relative color reflectivity is readily and accurately indicated on the cathode ray screen as illustrated in Fig. 7 have been measured in the laboratory to determine the actual color reflectivity thereof by comparison with a standard. The following percentages of light reflecting characteristics were established:

Article	Description	Green	Red
<i>a</i>	Dark green lemon	23	12
<i>b</i>	Light green lemon	38	26
<i>c</i>	Green apple	52.5	36
<i>d</i>	"Silver" lemon	65	67.5
<i>e</i>	Ripe lemon	57	77.5
<i>f</i>	Orange	26	77
<i>g</i>	Dark red apple	5	26
<i>h</i>	Magnesium carbonate block	100	100
<i>i</i>	Tangerine	19	60

These figures, determined by actual laboratory measurement, correspond exactly with the indications of hue and brightness as determined for the same articles by the scanner and cathode ray tube arrangement of my invention. Were a chart similar to that of Fig. 7 superposed on the cathode ray tube screen, it would be possible to instantly and exactly ascertain the light reflecting characteristic of any article as expressed in terms of the percentage reflectivity of any two different colors present in the article by employing suitable filters.

It is well known that the luminous spot on the screen of a cathode ray tube may be deflected in two independent directions by voltages applied to certain deflecting electrodes or plates, and in the embodiment of my invention illustrated, the voltages representing the two reflectivity measurements are so applied to the deflecting plates of cathode ray tubes as to delineate both the hue and brightness as shown in Fig. 7.

By means of the scintillator brush and associated mechanism to be explained later, it is provided that the cathode beam is extinguished most of the time, appearing only momentarily when the object is centered in the field of view. Thus, each object is represented by a dot of light on the screen and it is evident that by covering any desired sections of the screen with opaque material the scintillations corresponding with certain colors and brightnesses would not be visible to an observer. In the embodiment of my invention illustrated, such masks are employed to prescribe the types of lemons to be accepted or rejected.

The observer is represented by a "sentinel" photo-tube and associated mechanism ever alert to detect the scintillation and register its appearance by a charge on the delay commutator or detainer, to be described, which, after an interval sufficient to bring the lemon before one of the ejectors, actuates that ejector and removes the lemon.

The particular color of the filters employed and the type of photo-tube are of course susceptible of change depending upon the nature of the articles being judged. Red and green filters are preferable in the sorting of citrus fruits, such as lemons, oranges, and the like, for obvious reasons.

The construction and operation of the cathode ray tube are in general known; however, it may be well to state briefly the principles of operation of the same with reference to the

manner in which it is related to the present invention.

In general, a cathode ray tube consists of an evacuated or gas filled envelope wherein are mounted a cathode adapted to emit a stream of electrons when heated and means for heating the same, a plurality of control grids or electrodes, usually two, an anode cooperable with said electrode in accelerating and focusing the stream of electrons emitted from the cathode when the same is heated into a beam, and a plurality of vertical and horizontal deflection plates, four in number, arranged in pairs above and below and at the sides of the said beam. These deflection plates are connected to potential sources, the horizontal to one source and the vertical to another source. In a balanced or neutral condition of the plates, the electron stream flowing therebetween is in the form of a straight line beam from the cathode longitudinally and centrally of the tube. The end of the tube is coated with a fluorescent preparation which, when struck by the negative electron particles of the beam, becomes luminous at the point struck. If one of the horizontal deflection plates be rendered negative in charge relative to the other, the negative stream of electrons will be deflected away from the lower potential plate and towards the higher. The same situation obtains relative to the charging of the vertical deflecting plates; i. e., the stream will be deflected vertically towards the plate at higher potential and away from the plate at lower potential.

Applying these principles to my adaptation of the cathode ray tube, it is apparent that impulses originating in scanner tubes 35, 36, 37, and 38, by causing the beam trace to be deflected to one side or the other of the theoretical line "black" to "white" in the diagram, accurately indicate the relative color reflectivity, or the hue of an article scanned, while the distance the trace is deflected along one of the isochromatic lines, such as *mp* or *mn*, or from the black apex, gives a measurement of the brightness of the reflected light, whatever its hue may be.

It will be apparent to those skilled in the art from the description so far that my scanning and cathode ray translating apparatus is capable of being considerably altered without affecting the manner of operation thereof. For example, instead of employing a pair of "red" and a pair of "green" filtered scanner tubes with the tubes of each pair generating separate impulses, which are later blended to furnish separate composite "red" and "green" impulses, it is of course possible that two independent views of the article may be made, one on each side thereof, thereafter blending the two views and exposing a pair of photo-tubes to the resultant blended view through two red and green filters, respectively. In other words, the light could be mixed rather than the electrical impulses resulting from the light. This, of course, would cut down the number of photo-tubes and filters from four to two and minimize any possible difficulty of photo-tube matching.

It may be found to be of advantage in assuring a strong signal from sentinel tube 14 to adopt as a screen material for the cathode ray tube one of the well known series of materials giving a red trace, so that a powerful caesium photo-tube can be used as the sentinel tube. This would enable the sentinel to pick up the cathode ray trace without great sensitivity demands upon the sentinel amplifier.

As a possible further modification of my invention, coming within the scope of the appended claims, it is indeed quite possible that the sentinel tube might be omitted entirely so long as some other means were provided to initiate a secondary signal in accordance with the position of the cathode ray beam. For example, as illustrated in Fig. 8, by employing a suitable sensitive foil or plate 410 inside or outside the cathode ray tube envelope connected to a take-off lead 411, it is conceivable that the beam falling on such an element could suffice to bias a gas filled discharge tube directly, without the intervention of either a photo-tube or an amplifier. Of course, the inability to conveniently alter the shape of such an element to alter the type of objects sorted would interfere with the commercial practicality of such an expedient. However, it is referred to as a possible extension of the basic idea of the present machine.

Primary impulses originating in scanner tubes 35 and/or 38 are amplified by a two-stage amplifier generally indicated by the reference numeral 42, including a pair of triodes 43, 44 of the type generally designated as "56" and technically known as unipotential cathode triodes, while scanner tubes 36, 37 are connected to a similar amplifier. In view of the fact that the wiring for the amplifier circuits for tubes 35, 38 on the one hand and tubes 36, 37 on the other hand, is identical, only one thereof will be described and corresponding reference numerals will be used for the other.

The output of amplifier 42 is impressed on a cathode ray tube 13. There are a plurality of such cathode ray tubes, the number thereof depending upon the number of hammers or ejectors 7 which it is desired to actuate, and each cathode ray tube is connected so as to be capable of actuating any one of the hammers. For the purpose of simplification, only one of these identical cathode ray tube-to-hammer circuits will be described. The corresponding parts of the other circuits will be denoted by similar reference numerals. It should be understood, however, that the number of cathode ray tubes which may be employed is in no way limited and if it were desired to sort articles into five, ten, or more receptacles, a mere multiplication of the elements and connections which I shall describe would accomplish this result.

Cathode ray tube 13 has mounted adjacent thereto a photoelectric tube 14 which is adapted to be selectively exposed or not to the beam trace on the screen of the cathode ray tube, depending upon whether the mask 15 thereon permits said beam trace to reach, or prevents it from reaching, the photoelectric tube 14 and thereby originating what may be termed a secondary impulse or signal. Because of the function which it fulfills, the said photo-tube is referred to as a sentinel tube.

Regarding mask 15, it may be formed of any material which is opaque and capable of having a light admitting opening or openings formed therein. In developing this invention and in actual practice in the machine illustrated, I have found that ordinary electrician's adhesive tape is admirably well suited to this purpose, inasmuch as it is opaque and a plurality of strips thereof may be adhered to the outside of the screen in any desired position so as to mask off all portions of the screen except a predetermined area or areas through which the beam trace is to be viewed by the photoelectric sentinel tube 13 or 75

which is to activate the sentinel tube. In this connection, reference is again made to the latitude available in disposing the masks on the screen to sort a wide range of colors, no matter what the construction of the mask per se may be. As stated above, all of the screen may be rendered opaque except a certain small area whereby to pass the beam trace when caused to be deflected to that area by a certain small range of colors. 10 This area may be enlarged at will to increase the range of the said color, or on the other hand a smaller or larger area may be rendered opaque whereby all articles save those in the range protected by that area will be ejected. 15 Other manipulations of the mask will suggest themselves. For example, the same may be made opaque throughout except in a plurality of portions, whereby to eject articles of different color causing a deflection of the beam to those various portions. 20 A further aspect of my invention resides in the fact that with the hammers disconnected a number of articles may be placed on the article conveyor, for example, articles of various colors other than a given standard acceptable color. If a photograph of the entirely exposed cathode ray screen be now taken, so as to record on a negative photographic film the positions of the luminous trace under the various influences of the different colored articles and controlled by the scintillator mechanism to be described, it is apparent that a positive transparency of the negative may thereafter be employed as a mask for the cathode ray tube, thus eliminating the necessity of 25 making individual masks each time a group of articles is to be sorted. On the other hand, if a group of standard colored articles, all acceptable, be employed as test objects and the exposed screen photographed, the resultant negative may be used as a standard mask which will thereafter govern the cathode ray tube 13 and sentinel 14 to initiate ejection of all articles other than the acceptable standard colors. From this it appears that the device of my invention lends itself to use 30 in making its own control elements.

The secondary impulses originating in sentinel tube 14 are amplified by the multiple-stage amplifier tube 45 and pass from the plate thereof to a grid controlled gaseous discharge tube 46. The plate of this tube is connected to a selector switch 47. The grid controlled gaseous discharge tube 48 furnishes the actual signal which actuates the electromagnetic ejector mechanism 6, but between tube 48 and selector switch 47 I interpose the delay commutator or detainer 17, which times impulses on the grid of tube 48 so that they occur only when an article seat 3 is directly before a hammer 7. Detainer 17 withholds ionization of discharge tube 46 until a secondary impulse has been impressed on the grid thereof. When this happens, the condition of the detainer is altered by a condenser discharge, to be described, with the result that after a predetermined interval, the discharge tube 48 is fired and the ejector actuated.

I preferably provide means in the form of a suitable conducting lug on rotary switch 18, engaged by a scintillator brush, to ignite the cathode ray tube only intermittently and during a very short period in the scanning cycle, namely, when the articles being sorted are exactly in scanning position before the scanner tube, or, if desired, midway between articles. This causes the sentinel 14 to view a beam trace in the form of a small distinct dot. Such provision, of course,

greatly increases the life of the cathode ray tube, which would be likely to wear out or crack in a relatively short time were it permitted to operate continuously.

The various particulars of the hookup will now be described. The reference numeral 49 indicates an alternator or source of alternating current, the terminals of which are connected to the primary 50 of a transformer 51 having a plurality of secondary coils. From certain of these coils I derive a potential, rectified through the all-wave rectifier 52, for the anode circuits of the scanner tubes and the amplifiers described above, the said potential being smoothed out by the pulsation eliminating chokes 53, 54 and condensers 55, 56 across the terminals thereof. Other of the secondaries furnish a voltage which is rectified by the half-wave rectifier tube 57. This voltage traverses a 30,000-ohm resistor 58 and serves as a fixed potential for the cathode ray anode.

The cathode ray grid voltage is controllable by the 20,000-ohm potentiometer 59. The voltage for the first anode of the cathode ray tube is controllable by an adjustable tap on the 36,000-ohm potentiometer 60. The voltage dropping resistors 63, 74 of 33,000 and 100,000 ohms respectively, along with potentiometers 59, 60, constitute a voltage divider generally designated 61. The filament of the cathode ray tube is connected to the transformer filament winding as indicated by the reference characters x, y. One of the horizontal and one of the vertical deflecting plates, as well as the second anode, of the cathode ray tube are connected to ground at 62. The control grid and first anode voltages are variable by adjusting potentiometers 59 and 60. A resistance 65 of 1 megohm is included in the line from the adjustable tap on potentiometer 59 to the cathode ray tube.

A voltage divider, generally indicated by the reference numeral 66, made up of a 1000-ohm resistor 67, a 100-ohm resistor 68, a 100-ohm potentiometer 69, a 20-ohm resistor 70, a 60-ohm potentiometer 71, a 2000-ohm resistor 72, and a 200-ohm resistor 73, is connected between the output of rectifier 52 and a further voltage divider, generally indicated by the reference numeral 74, which is employed for energizing the scanner tubes and amplifier 42 and for matching and controlling the same. The anodes of scanner tubes 35, 36, 37, 38 are adjustably tapped to parallel 4000-ohm potentiometers 75, 76 respectively in the last named voltage divider, and a suitable high resistance 77, say of 3 megohms, is interposed between the cathodes of those tubes and the minus side of the scanner amplifier voltage divider 74. Aside from potentiometers 75, 76, the voltage divider 74 consists of the 40-ohm resistor 78, the 200-ohm potentiometer 79, the 20-ohm resistor 80, the 700-ohm resistor 81, the 100-ohm potentiometer 82, and the 55-ohm resistors 83. The cathodes of amplifier tubes 43, 44 are connected to the adjustable tap of potentiometers 82 and 79 as illustrated.

The plate of the triode amplifier 43 is connected to the grid of amplifier 44 through a .25-microfarad condenser 85; i. e., the two amplifier tubes are capacity-coupled. A normalizing switch 86 is placed in shunt from a point between condenser 85 and the grid of tube 44 to a point between resistors 80 and 81 in the scanner amplifier voltage divider.

In practice, this switch 86 takes the form of a rotary commutator having a circuit-making conducting lug thereon, substantially as disclosed

in my Patent No. 2,131,096, dated September 27, 1938, this commutator being driven in synchronism with the conveyor 2 so as to momentarily close a circuit through switch 86 between scanning periods from the grid of tube 44 to voltage divider 74. The said commutator may conveniently be arranged as a part of rotary switch 13, but the actual detail of construction has not been shown, in order to avoid complicating and confusing the disclosure. Suffice it to say that the said recurrently actuated switch 86 serves to establish a suitable bias on the grid of tube 44 each time the same is closed. This instantaneous setting of the tube to a normal condition between scanning operations I refer to as "normalizing."

The plate of amplifier tube 43 is connected to the plus side of the voltage divider 74 through a 5000-ohm resistor 87.

The plate of amplifier tube 44 is connected through a 200,000-ohm resistor 88 to the plus side of resistor 73 of voltage divider 66. The output of the "red" scanner amplifier tube 44 is connected to the vertical deflection plates of the various cathode ray tubes, while the output of amplifier tube 44 for the "green" scanners is applied to the horizontal deflection plates of the various cathode ray tubes.

Potential for the anode of sentinel tube 14 adjacent cathode ray tube 13 is supplied from a connection to the voltage divider 66 between resistors 72 and 73 and this source likewise serves to supply a plate voltage for the plates of the twin triode amplifier tube 45, which is the type generally referred to as a "53." The cathode of sentinel tube 14 and the first grid of tube 45 are connected to ground through a suitable high resistor 89 of 15 megohms. Resistors 90, 91 are 200,000-ohm plate circuit resistors for tube 45, and the grid bias for tube 45 is controlled by an adjustable tap on resistor 71.

The cathode of the sentinel tube 14 is connected to the first grid of the twin triode tube 45 and the plate of the first triode element of tube 45 is connected to the grid of the second triode element of that tube through the 0.1-microfarad condenser 92 so as to effect a capacity-coupling therein, and the said last named grid has a 0.2-megohm resistor 93 between the same and ground.

The output of the amplifier tube 45 is impressed on the grid of the small grid controlled gaseous discharge tube 46 through a 0.1-microfarad condenser 94 and a 10,000-ohm resistor 95. A 0.2-megohm resistor 96 is inserted between the discharge side of condenser 95 and an adjustable tap on voltage divider resistor 69 to vary the bias on the grid of tube 46. A 0.01-microfarad condenser 97 between the grid of tube 46 and ground serves to avoid hesitation in the performance of tube 46. The cathode of tube 46 is connected between the 2900-ohm and 30,000-ohm resistances 98, 99, respectively, of a voltage divider generally designated 100, and also to ground through the 0.1-microfarad condenser 101. One end of voltage divider 100 is connected to ground and the other end is connected through conductor 102 to a line which in turn is connected to the filtered 150-volt D. C. source 103.

The plate of gaseous discharge tube 46 is connected to the selector switch 41, the various contact lugs of which are connected with brushes on delay commutator or detainer 17. By this switch, I am able to connect the gaseous dis-

charge tube 48 actuating any one of ejector hammers 7 with any one of the cathode ray tube circuits. As illustrated, the switches 47 are arranged to connect their respective cathode ray circuits with the gaseous discharge tube circuits immediately adjacent the same. However, the arrangement might be an entirely different one or, if desired, one or more of the switches might be disposed in off position so as not to make connection with any of the discharge tube circuits.

The contact lugs of switch 47 are each connected through a 6000-ohm resistor 104 to a brush 105 riding on the periphery of detainer 17. This detainer carries a plurality of spaced sets 106 of condenser and brush engaging conducting elements or lugs, the condensers and conducting lugs being indicated by the reference numerals 107, 108 respectively. There are in the illustrated example six such sets spaced equally circumferentially of the detainer. Each set consists of three condensers 107 each having a plate connected to a conducting lug 108 and spaced axially along the detainer. The condensers 107 are of 0.25 microfarad capacity. The brushes 105 are spaced axially of the detainer to correspond to the axial spacing of the lugs and condensers, so that each brush engages one of the circumferentially aligned and spaced lugs 108 of the several sets. The other plate of each condenser is connected to a continuous conducting ring 109 on the detainer. It will be appreciated that the expedient of illustrating the elements of sets 106 in radial order has been adopted only to simplify the disclosure. It is believed that in the light of the foregoing description the actual circumferential and axial disposition of condensers 107, lugs 108, and brushes 105 will be clear.

I provide further peripherally and axially spaced brushes 110, one for each ejector hammer 7, these being connected respectively to one end of the three coils 111 of the iron core step-down transformers 112 in the discharge tube circuits. The other ends of the respective coils 111 are connected to a still further brush 113 which rides on the continuous conducting ring 109. Brush 113 is connected to the aforesaid D. C. source 103 through a 30-henry choke 213 and serves to maintain a charge on the innermost plate of condensers 107.

The three brushes 110 are spaced axially to engage the respective axially spaced lugs 108 and furthermore they are spaced peripherally from one another and from brushes 105 distances in proportion to the spacing of the three ejector hammers 7 from the viewing station or field in lamp housing 5. For example, with the hammer nearest the viewing field spaced a distance from the lamp housing equal to approximately the distance between three and one-half article seats on the conveyor wheel, the first brush 110 will be circumferentially spaced from brushes 105 a definite proportionate distance in the direction of movement of detainer 17. Since the second or middle hammer 7 is spaced from the first hammer a distance equal to the distance between article seats, the second brush 110 will be spaced from the first brush 110 a distance in the direction of detainer rotation which is in the same proportion, or, as it actually happens, a distance equal to the distance between sets 106. A similar consideration holds for the spacing of the third brush 110 from the second brush 110. The detainer 17 is so synchronized with the article carrying wheel 2 that the sets 106

are in engagement with brushes 105 at the moment an article on the wheel is being viewed by scanners 35, 36, 37, 38.

The foregoing construction of detainer and brushes constitutes a delay timing mechanism somewhat similar in function to the instrumentality described in my above mentioned Patent No. 2,131,096, and therein referred to as an isochronous ejector mechanism. The present timing or delay mechanism is shown and claimed in my copending application Serial No. 244,821, filed December 9, 1938. An impulse originating in sentinel tube 14 and considerably amplified through amplifier tube 45 will be impressed on the grid of gaseous discharge tube 46 at the instant an article is scanned, assuming that the cathode ray trace has been permitted by mask 15 to impinge the sentinel tube. At this same instant, brushes 105 engage lugs 108. Immediately prior to this engagement, the plates of condensers 107 are in an equally charged condition, by reason of the voltage impressed thereon through brushes 110 and 113 from source 103, and when the engagement of lug 108 and brush 105 takes place the outermost condenser plate discharges on the plate of one of the tubes 46, depending on the setting of switch 47, causing that tube to fire. In the event that no impulse or signal has been received on the grid of tube 46, of course, ionization will not take place. The bias of tube 46 may be properly set by an adjustable tap on potentiometer 11 to a suitable value. The events attending the scanning of the article and the ionization or non-ionization of tube 46 may be regarded as occurring in what may be termed an instantaneous scanning and signalling period.

The detainer 17 now rotates until the conducting lugs 108 reach and engage brushes 110. Since the outermost plate of one of the condensers 107 has been assumed to have discharged, it follows that that condenser is in an unbalanced condition so that when its lug 108 engages the corresponding brush 110 the plates of the condenser will be short-circuited. This short circuit includes the coil 111 of transformer 112 and the result is that a distinct signal is sent through the secondary coil 114 of the transformer onto the grid of gaseous discharge tube 48. The interval during the rotation of detainer 17 to bring the lugs 108 into contact with one or another of brushes 110 corresponds to the time required for conveyor wheel 2 to transport an article from the housing 5 to a position before one or another of the ejector hammers 7. It may be designated the detaining or timing and ejecting period.

It need hardly be stated that if the tube 46 has not been fired, then condensers 107 remain in balanced condition and the tube 48 is not lighted.

I illustrate six sets 106 of condensers and conducting lugs. Detainer 17 is driven in synchronism with article carrying wheel 2 so far as the linear speed of the article bearing seats and sets 106 is concerned. Therefore, in the embodiment shown, detainer 17 will make one revolution in the length of time that it takes six article seats to pass a given fixed point, or stated otherwise, the length of time between the departure of one set of conducting lugs 108 from angular alignment with brushes 105 and the arrival of a succeeding set is exactly equal to the length of time consumed by one article seat in passing from a point in front of one hammer 7 to a point in front of the succeeding hammer.

A 15,000-ohm resonance damping resistor 115

is disposed between the terminals of coil 111. The grid of tube 48 is given suitable bias by connecting the same through a 50,000-ohm resistor 116 and coil 114 to a point on voltage divider 66 between resistors 67 and 68.

A 0.02-microfarad condenser 117 is connected between resistor 116 and the grid of tube 48 and to ground, with the cathode of tube 48 connected between the condenser and ground.

The plate of discharge tube 48 is connected to the coil 118 of an electromagnet, the core 119 of which functions to actuate hammer 7. The said coil is connected through a 5-ohm resistor 120 to a brush 121 bearing on rotary switch 18, through which plate current for tube 48 is transmitted during the ejecting period.

A scintillator brush 122 and a further brush 123 also bear on the rotary switch and are connected through a 0.05-microfarad condenser 124 and a 500-ohm resistor 125. Brush 123 is in engagement with a continuous conducting ring 126 on the rotary switch, while scintillator brush 122 periodically engages a relatively small conducting segment 127 thereon.

The said segment 127 and conducting ring 126 are in conducting relation to or integral with the large or semi-circular conducting segment 128, which latter segment is engaged by brush 121 during one-half of each rotation of rotary switch 18. The rotary switch is, as pointed out above, driven in predetermined relation to the speed of detainer 11, in this case, six times as fast, so that the rotary switch makes one revolution between the departure of an article seat from a given point and the arrival of the succeeding article seat at that point. In other words, rotary switch 18 performs one cycle of its operations for each article.

When the small segment 127 is in engagement with scintillator brush 122, the cathode ray tube 13 is energized by a surge passing through 0.01-microfarad condenser 132. This takes place at the exact instant that an article is being scanned by scanner tubes 35, 36, 37, 38; during the remainder of the cycle of rotation of switch 18 the cathode ray tube is extinguished. Thus, the life of the tube is greatly increased.

The tapped resistor 130 permits a suitable fraction of the voltage picked up by brush 122 to reach and fire the cathode ray tube.

In practice, I have found it desirable in setting the machine to be able to light the cathode ray tube during an instant when the space between article seats is at the scanners, as well as when the seats themselves are in position for scanning. To this end I furnish a second scintillator brush bearing on rotary switch 18 diametrically opposite brush 122, and designated by the reference numeral 122'. The connections from this brush to the cathode ray tube are similar to or common with those from brush 122 to the tube so that like reference numerals primed will be employed to identify the secondary connections. The two-pole manually controlled switch 129 is provided to enable brush 122 or 122' to be employed to cause the cathode ray tube to be energized at or between article seats, as will be understood.

Assuming brush 122 to engage segment 121, then a circuit is completed from voltage source 103 through brush 123, ring 126, segment 121, brush 122, resistor 125, switch 129, a suitable resistor 130, and conductor 131 to the parallel condensers 132. Each cathode ray tube 13 has a control grid connected to one side of one of these condensers. This control grid must have

a plus voltage impressed thereon for the tube to light and if the same goes negative the tube will extinguish. Therefore, the scintillator signal charges the said grid for an instant, causing tube 13 to produce an instantaneous electron beam trace, which impinges on sentinel tube 14 or is intercepted by mask 15, as the case may be. When the segment 127 passes brush 122, the tube 13 goes out, the grid charge referred to leaking off through resistor 65 and the adjustable tap on potentiometer 59, which is set appropriately for this purpose.

The normal plate voltage for discharge tube 48 during the ejecting period is derived from voltage source 103 through brush 123, large conducting segment 128, brush 121 (during the half revolution of the rotary switch 18 when the last named brush and segment are in conducting engagement), and through the resistor 120 and electromagnet coil 118. The grid of tube 48 is connected by conductor 133 to a point on voltage divider 66 between the resistors 67 and 68 thereof. The values of the grid bias and the plate voltage for tube 48 are such that the tube is barely held from ignition during the engagement of brush 121 and large segment 128, and in order to trip electromagnet core 119, it is necessary that a further signal be impressed on the coil of transformer 112. This signal comes from transformer secondary 114, as explained, and when it occurs, tube 48 ionizes and hammer 7 trips.

The 4-microfarad condenser 134 and 16,000-ohm resistor 135 arranged in series between electromagnet coil 118 and voltage source 103 serve to prevent sparking.

The 16-microfarad condenser 136, in conjunction with choke 213, constitutes a filter to quiet that part of the direct current used by the detainer.

From the foregoing, it is apparent that the present machine will sort articles through a very large range of color variations as manifested in relative color reflectivity. It is to be emphasized that the sorting of this large range of colors is not on the basis of merely the presence or absence of an impulse in the photoelectric tube scanners as has been the case in hitherto known photoelectric sorting machines, but on the contrary, the sorting of such a range of color compositions depends on the relative strength of the impulses generated in the red and green filtered scanner tubes, which impulses accurately reflect the percentage color composition and relative brightness of colors in the article and result in displacement of the cathode ray trace in exact accordance with such composition and brightness.

For each of the combinations of signals originated in the four scanner tubes there is a corresponding point on the cathode ray screen to which the cathode ray beam trace is deflected; actuation of the ejector hammers 7 may be initiated by whichever of such signals is desired by appropriately masking the screen.

A feature of considerable practical value and importance in the machine of my invention resides in the ease with which any difficulties causing the same to operate improperly may be traced. Thus, for example, if it is found that an ejector hammer 7 is being actuated to displace an article from the conveyor wheel when such displacement should not take place, or if it is found, on the other hand, that a hammer fails to act when it should, it is only necessary to remove the shield for the sentinel tube 14 and observe the screen of cathode ray tube 13 and the occurrence of the

beam trace thereon relative to the mask opening or openings. If the beam is visible when it should be visible, i. e., when an article should be ejected, then of course it follows that the trouble lies somewhere behind, or on the ejector side of, the cathode ray tube, which considerably narrows the field to be checked. If, on the other hand, the beam trace is not visible through the mask when it should be visible, then it follows that failure of the hammer to act is caused by some difficulty in front of, or on the scanner side of, the cathode ray tube, which may accordingly be checked without disturbing the apparatus behind the said tube. In this manner, the cathode ray tubes, because of their characteristic of permitting visual analysis of the voltages impressed thereon, are of great importance in my application thereof.

The herein disclosed device for delaying the actuation of the ejector, namely, detainer 17, operates as described above to insure that, once the impulses emanating from the sentinel tubes 14 have been ascertained and recognized by the ionization of tube 46, the ejector will be actuated at a definite time interval thereafter. By this arrangement, perfect timing of the hammers is provided for, which is of considerable importance in view of the fact that the various article judging, impulse amplifying, and impulse transmitting elements of the machine are instantaneous in action and accordingly capable of being operated at exceedingly high speeds. With such potential high speeds of operation, it becomes of primary importance to assure that the mechanical elements of the machine are precisely and practically instantaneously actuated. The detainer 17 and elements associated therewith insure such action.

The foregoing description of my invention relates to an embodiment thereof in a machine for sorting articles on the basis of the relative color reflectivity thereof, but it will be apparent to those skilled in the art that the invention has broader aspects, that the structure described, with minor alterations, can be adapted for the sorting of practically any articles on the basis of several different factors other than relative color reflectivity, such as weight, hardness, strength, etc., whether such factors are made independent of or dependent on one another. Moreover, the machine may be readily adapted for the sorting of elongated objects, such as, for example, asparagus stalks, by the simple expedient of providing a conventional time sweep voltage impressed on one of the deflecting plates. By such provision, the cathode ray beam could be swept horizontally by a sawtooth voltage and vertically with a single impulse proportional to the brightness of the object. Using an appropriate mask providing individual brightness tolerances to each section of the length of the object, it is apparent that any inverted stalks or stalks of incorrect length could be rejected.

Utilizing the principle of my invention, it is, moreover, theoretically possible to extend the system to cover a three-color process employing a double-beam cathode ray tube. This possibility is limited by the fact that the sum of the three-color measurements must be a constant, which is never the case with reflectivities. In the overwhelming number of cases in the commercial sorting field, analysis on the basis of two-color reflectivities is ample. Should a case occur requiring three-color analysis, it could be very simply handled by the structure shown and described by passing the objects first through a

machine operating on the basis of red and green light, for example, then through another operating on the basis of, say, green and blue light for a further sub-division.

5 The normalizing provisions of this machine are also of considerable importance since they assure an independent judging of each article by resetting the scanner amplifier to original condition after each scanning period.

10 Further advantages of the instant device will be obvious. As previously stated, I regard the provision of a cathode ray tube in combination with a sentinel photo-tube and a mask or other governing means between said tubes, to be used as an actuating and control mechanism, as broadly novel with me. This arrangement constitutes a device which is of wide utility. In my copending application, Serial No. 222,788, filed August 3, 1938, I disclose and claim such

15 means in various important general applications or adaptations.

20

I have illustrated and described my invention in embodiments which I have found highly satisfactory. I have not attempted to illustrate or 25 describe other embodiments or adaptations as it is believed that this disclosure will enable those skilled in the art to embody or adapt my invention as may be desired.

Having thus described my invention, what I 30 claim as new and desire to secure by Letters Patent is:

35 1. In a machine for assorting articles according to color, article scanning means adapted to originate an electrical impulse, article ejecting means, and means for actuating said ejecting means in accordance with variations in light reflectivity of the articles as viewed by said scanning means, comprising a cathode ray tube having one of the deflection plates thereof connected to said scanning means and adapted to be actuated thereby to deflect the cathode ray beam, in one direction, further impulse originating means connected to another deflection plate of the tube for deflecting said beam transversely 40 of said first named direction, light-sensitive means adjacent the cathode ray tube adapted to view the trace of said beam in certain of the resultant positions of the same on the cathode ray screen produced by said impulse originating 45 means, and means for controlling the positions of the beam trace in which the same is viewed by said light-sensitive means.

50 2. In a machine for assorting articles according to color, a cathode ray tube having beam deflection plates, means for originating a pair of independently variable signals including photoelectric article scanning means adapted to view articles, means for operating on said articles, and means for actuating said operating means 55 in accordance with the variations in relative intensity of light reflected from the articles, said cathode ray tube having one of the deflection plates thereof connected to said scanning means and adapted to be energized thereby to deflect the cathode ray beam in one direction, another of the deflection plates being connected to said first named means whereby to deflect the beam transversely of said first named direction, and light-sensitive means adjacent the cathode ray tube adapted to view the beam trace in certain 60 positions of the same.

65 3. Control and actuating means for an article sorting machine of the type described comprising a cathode ray tube, electrical means including means operable in accordance with one or 70 75

more characteristics of an article to be sorted, said first named means being connected to said tube for controlling the positioning of the beam thereof in a plurality of directions transversely of the screen of the tube, photoelectric viewing means disposed adjacent the screen of said tube, means between said viewing means and said tube for selectively exposing said screen whereby to mask the beam trace of the cathode ray tube from the viewing means in various positions of the beam, said viewing means viewing the trace in other positions thereof and generating electrical impulses accordingly, and an ejector mechanism controllable in response to said impulses.

4. In a machine of the type described, the combination of a beam emitting tube having a viewing screen, means connected to said tube for originating a primary impulse in accordance with a predetermined characteristic of articles to be operated on, and operative to deflect the beam of the tube in one direction, further impulse originating means connected to the tube to deflect the beam in a direction transverse said first named direction, said impulse originating means coating to control the positioning of the beam laterally and longitudinally of the screen of the tube, light-sensitive viewing means disposed adjacent the screen of said tube, means for selectively exposing said viewing means to said screen whereby to mask the beam spot of the cathode ray tube on the screen from the viewing means in various positions of the beam spot, said viewing means viewing the beam spot in other positions thereof, means for operating on the articles, and means controlled by said viewing means for actuating said operating means.

5. In a machine for sorting articles according to color, the combination of article illuminating means, plural impulse originating means including means for scanning the articles while subject to said illuminating means, article ejecting means, means for actuating said article ejecting means in accordance with variations in the articles as viewed by said scanning means comprising a cathode ray tube having beam deflecting means operatively connected to said plural impulse originating means to deflect the beam of the tube in two directions transverse to one another, and light-sensitive means operatively associated with said cathode ray tube and adapted to view the beam trace of said tube in certain positions only on the cathode ray screen.

6. In a machine for sorting articles according to color, the combination of plural article scanning means, article ejecting means, means for actuating said article ejecting means in accordance with variations in relative color reflectivity of the articles as viewed by said scanning means comprising a cathode ray tube having beam deflecting means operatively associated with said plural scanning means to deflect the beam of the tube in two directions transverse to one another on the screen of the tube, and light-sensitive means operatively associated with said cathode ray tube and adapted to view the beam trace in certain positions only on the cathode ray screen.

7. In a machine for sorting articles according to color, the combination of plural article scanning means, article ejecting means, means for actuating said article ejecting means in accordance with variations in relative color reflectivity of the articles as viewed by said scanning

means comprising means for emitting a beam producing a luminous trace, said emitting means having beam controlling means operatively connected to said plural impulse originating means to deflect the beam in two directions transverse to one another, and light-sensitive means adapted to generate electrical impulses in response to said beam under certain predetermined conditions thereof controlled by said controlling means.

8. In an article sorting machine, the combination of a cathode ray tube, article judging means adapted to originate a primary impulse in accordance with a characteristic of the articles and 15 operatively associated with the beam deflecting means of said cathode ray tube whereby the beam trace is caused to traverse the cathode ray screen in one direction in accordance with the variations in the primary impulse, further impulse originating means connected to said beam deflecting means and operative to deflect the beam in a direction transverse the first named direction, the resultant positioning of the beam being determined by the coating effects of said 20 primary and further impulse originating means, light-sensitive activating means operatively associated with the screen of said cathode ray tube, and means for selectively exposing said light-sensitive activating means to the trace of the 25 cathode ray tube beam in various positions of the beam.

9. In a machine for sorting articles on the basis of relative color reflectivity, the combination of a cathode ray tube, primary impulse initiating and transmitting means operatively associated with the beam deflecting means of said cathode ray tube, said first named means actuating the deflecting means to cause the beam trace to be deflected in one dimension in accordance with the intensity of one reflected color and in another dimension in accordance with the intensity of another reflected color, and light-sensitive means operatively associated with said cathode ray tube and activated by the beam trace.

10. In a classifying machine, the combination of a cathode ray tube, plural impulse originating means including article judging means adapted to originate a primary impulse, said plural impulse originating means being connected to said cathode ray tube whereby to control the positioning of the beam thereof in two directions transverse to one another in accordance with the variations in the impulses originated by said first named means, light-sensitive activating means operatively associated with the screen of said cathode ray tube and exposed for energization by the trace of said beam in accordance with variations in the positioning thereof effected by said impulses, article classifying means, and means controlled by said light sensitive activating means for actuating said classifying means.

11. In a machine of the type described, means for scanning articles and initiating impulses proportional in intensity to the intensity of light reflected from the articles, further impulse initiating means, a cathode ray tube, means connecting said tube to said impulse initiating means to control the lateral positioning of the electron beam of the tube in two directions transverse to one another in accordance with said impulses, light-sensitive means distinct from said first named for viewing the trace of said beam, said last named means initiating impulses in accordance with the controlled condition of the beam,

and means for limiting the effective range of said light-sensitive means with reference to the screen of the tube.

12. In a sorting or like machine, separate impulse originating means including light-sensitive means for scanning articles, said first named means simultaneously initiating separate sets of electrical impulses at least one of which is impulses proportional in intensity to the intensity of light reflected from the articles, a cathode ray tube having the deflecting plates thereof connected respectively to said first named separate means whereby the electron beam of the cathode ray tube assumes various positions laterally and longitudinally of the screen of the tube in accordance with the intensity of said impulses, light-sensitive means for viewing the trace of said beam in certain of said positions and activated thereby in those positions, article shifting means, and means controlled by said light sensitive viewing means for actuating said shifting means.

13. In a machine for sorting articles according to color, the combination of plural article scanning means, article ejecting means, means for actuating said article ejecting means in accordance with variations in relative color reflectivity of the articles as viewed by said scanning means comprising a cathode ray tube having plural beam deflecting means connected to said respective scanning means whereby the point of impingement of the beam on the cathode ray screen shifts in two directions transverse to one another with variations in relative color reflectivity of the articles scanned by said scanning means, and light-sensitive means operatively associated with said cathode ray tube and activated by the beam trace thereof in certain positions only on the cathode ray screen.

14. The combination of a pair of article scanning means, a cathode ray tube having a screen and plural beam deflecting means disposed at an angle to one another and operatively associated with and controlled by said respective scanning means whereby the beam of the tube is deflected in two directions transverse to one another on the screen, so that the point of impingement of the beam on the cathode ray screen is selectively positioned on any portion thereof in accordance with variations in the scanned articles, light-sensitive means operatively associated with said cathode ray tube and activated by the beam in certain positions only, and means acting on the articles scanned operatively associated with said light-sensitive means.

15. The combination of a pair of electrical impulse originating means including article scanning means, a cathode ray tube having a pair of beam deflecting means disposed at an angle to one another and connected to said respective impulse originating means whereby the beam of the tube is deflected longitudinally and laterally relative to the screen of the tube and the point of impingement of the beam on the cathode ray screen is selectively positioned on any portion thereof in accordance with variations in the impulses, means operatively associated with said cathode ray tube and activated by the beam in certain positions only, and means acting on the articles scanned operatively associated with said last named means.

16. In a machine for sorting articles according to color, an article scanning means, means for translating articles successively to said scanning means, means for selectively ejecting arti-

cles from said translating means including a plurality of ejecting members operatively associated with said translating means, a cathode ray tube for each ejecting means, said cathode ray tubes having the beam deflecting means thereof operatively associated with said scanning means, adjustable masking means for the cathode ray screens of said tubes leaving only a portion thereof exposed for the transmission of light, a light-sensitive means operatively associated with each cathode ray tube screen, and means for transmitting signals from said light-sensitive means and for imposing corresponding actuating impulses on said ejecting means in timed relation to said translating means.

17. In a machine for sorting articles according to color, an article scanning means, means for translating articles successively to said scanning means, means for selectively ejecting articles from said translating means including a plurality of ejecting means operatively associated with said translating means, a cathode ray tube for each ejecting means, said cathode ray tubes having the beam deflecting means thereof operatively associated with said scanning means, a light-sensitive means operatively associated with each cathode ray tube screen, and means operatively connecting said light-sensitive means with the ejecting means to initiate the actuation thereof.

18. In a sorting machine of the type described, means for scanning articles, a cathode ray tube, means connecting said scanning means to the plates of said cathode ray tube whereby to deflect the beam thereof in accordance with the relative color reflectivity of an article, means for controlling said cathode ray tube to cause a beam to be emitted thereby only when an article to be assorted is adjacent the scanning means, ejector means, and means for actuating said ejector means including a light-sensitive element adjacent the cathode ray tube and means for limiting the effective range of the light-sensitive element with reference to the beam trace on the screen of the cathode ray tube.

19. In a sorting or like machine, means for scanning articles, a cathode ray tube, means connecting said scanning means to said cathode ray tube whereby to control the beam thereof in one direction in accordance with the light reflectivity of an article, means connected to the tube for controlling the beam in a direction transverse to the first named direction, means for actuating said cathode ray tube to cause a beam to be periodically emitted thereby, article shifting means, and means actuated in response to the positioning of said beam by said controlling means for actuating said shifting means.

20. In a machine for sorting articles according to color, the combination of plural impulse originating means including article scanning means, article ejecting means, means for initiating the actuation of said article ejecting means, said initiating means being activated by said scanning means and comprising means for projecting and deflecting an electronic beam connected to said plural impulse originating means to deflect the beam in different directions transverse to one another, the deflecting of the beam being controlled at least in part by the scanning means as influenced by the articles scanned, and means activated by said beam when it is projected in a predetermined area of limited extent as compared to the area throughout which it is

projected as a result of the scanning of articles of varying hue and/or brightness.

21. In a sorting machine of the type described, intermittently operative article judging means, an electron emitting tube adapted to emit a beam of electrons and having means for controlling the position of the beam, means connecting said controlling means to said article judging means for deflecting the beam substantially simultaneously with the operation of said judging means, and means for initiating the emission of the beam only at that instant.

22. In a machine for sorting articles, photo-sensitive means for scanning the articles adapted to originate electrical impulses proportionate to a plurality of characteristics of the articles being sorted, sorting means, and means for controlling the actuation of said sorting means from said scanning means, comprising a device having a viewing screen and means for producing a visible signal on said screen, means electrically connecting said scanning means to said device for altering the position of said visible signal in accordance with said characteristics, and means adjacent said screen sensitive to said signal in certain positions of the same on the screen for initiating an impulse for activating said sorting means.

23. In a machine of the type described, photo-sensitive means for scanning articles to be operated on adapted to originate separate electrical impulses proportionate to a plurality of characteristics of the articles being sorted, means for operating on the articles, and means for controlling and actuating said operating means comprising a device having means for producing a visible signal, means electrically connecting said scanning means to said device for altering said visible signal in accordance with said separate impulses, and means sensitive to said signal for transmitting an activating impulse to said operating means.

24. In a machine of the type described, means for originating a pair of independently variable electrical signals, a cathode ray tube, means for amplifying and transmitting certain of said signals to one deflection plate of the cathode ray tube, means for amplifying and transmitting the other of said signals to another deflection plate of the cathode ray tube, means for restoring the amplifying means to a normal condition between transmission of signals, photoelectric means for viewing the cathode ray beam trace as deflected on the cathode ray screen under the influence of said signals, and means periodically placing said cathode ray tube in beam emitting condition.

25. In a machine of the type described, means for originating a pair of independently variable electrical signals, a cathode ray tube, means for amplifying and transmitting certain of said signals to one deflection plate of the cathode ray tube, means for amplifying and transmitting the other of said signals to another deflection plate of the cathode ray tube, photoelectric means for viewing the cathode ray beam trace as deflected on the cathode ray screen under the influence of said signals, and means periodically placing said cathode ray tube in beam emitting condition.

26. In a sorting machine of the type described, means for conveying a series of articles in spaced relation, photoelectric scanning means for viewing said articles, comprising a pair of photoelectric tubes each provided with a color filter different in color from the filter for the other whereby each filter isolates a certain part of the

light reflected from the articles, means for amplifying the separate impulses originating in said tubes, a cathode ray tube, means for connecting the output of said amplifying means to the deflecting plates of the cathode ray tube, means for periodically energizing said cathode ray tube to produce an electronic stream therein, variations in the charges on said deflecting plates causing the beam to be deflected on the cathode ray tube screen, photoelectric sentinel means adapted to view the beam trace on said screen, a control mask associated with said screen to expose said sentinel means to the beam trace in certain positions of the latter, an electrically actuated ejector, and means for amplifying and transmitting impulses originating in said sentinel means in response to said trace to said ejector including a device for timing said impulses so as to be effective on the ejector at predetermined intervals.

27. In a sorting machine of the type described, means for conveying a series of articles in spaced relation, photoelectric scanning means for viewing said articles, comprising a pair of photoelectric tubes each provided with a color filter different in color from the filter for the other whereby each filter isolates a certain part of the light reflected from the articles, a cathode ray tube, means for connecting the output of said scanning means to the deflecting plates of the cathode ray tube, means for energizing said cathode ray tube to produce an electronic stream therein, variations in the charges on said deflecting plates causing the beam to be deflected on the cathode ray tube screen, photoelectric sentinel means adapted to view the beam trace on said screen, an electrically actuated ejector, and means for amplifying and transmitting impulses originating in said sentinel means in response to said trace to said ejector including a device for timing said impulses so as to be effective on the ejector at predetermined intervals.

28. In a machine of the type described, photoelectric scanning means for viewing a plurality of spaced moving articles, comprising a pair of photoelectric tubes each of which is provided with a color filter different in color from the filter for the other, whereby to isolate predetermined components of the light reflected from the articles, separate means for amplifying impulses originating in said tubes and proportional to certain color reflectivity of the articles, a cathode ray tube, means for connecting the output of one of said amplifying means to one deflecting plate of the cathode ray tube, means for connecting the output of the other amplifying means to another deflecting plate of the cathode ray tube, and means for energizing said cathode ray tube to produce an electronic beam therein, said beam being deflected in one dimension in accordance with the intensity of one color and in another dimension in accordance with that of another color.

29. A sorting machine comprising an electron beam emitting tube having a screen toward which the beam is directed, light-sensitive means for scanning objects to be sorted connected to the tube to control the beam thereof in accordance with the relative color reflectivity of an object with reference to a plurality of colors, the beam of said tube impinging the screen thereof in various positions depending on said relative color reflectivity, and means for masking the beam trace on the screen in certain of said positions.
